UNITED STATES PATENT OFFICE.

CARL ALRIK HULT AND OSCAR WALFRID HULT, OF STOCKHOLM, SWEDEN.

OUTBOARD MOTOR.

1 207 261

Specification of Letters Patent. Patented Dec. 12, 1916.

Original application filed July 3, 1913, Serial No. 777,152. Divided and this application filed June 16, 1915.
Serial No. 34,332.

To all whom it may concern:

Be it known that we, **CARL ALRIK HULT** and **OSCAR WALFRID HULT**, subjects of the King of Sweden, residing at Stockholm, Sweden, have invented certain new and useful Improvements in Outboard Motors, of which the following is a specification.

Our invention relates to outboard motors for water craft, and is especially designed for use in connection with internal combustion or explosive motors the cylinders of which are arranged at the stern of the boat above the normal water line.

The present application is a division of
15 our co-pending application for patent, Se-
rial No. 777,152, filed July 3, 1913.

Our improved motor is one having an extended motor shaft, which, through intermediate gearing, is suitably connected to a propeller shaft and one of the characteristic features of the invention is to provide the motor casing with a depending sleeve surrounding the motor shaft, the sleeve and motor casing being relatively immovable whereby certain advantages, hereinafter more fully specified, are obtained in the operation of our device.

The invention is illustratively exemplified in the accompanying drawing as being applied to a two cylinder balanced motor, although it will be obvious that the invention might with equal facility be used in connection with a one cylinder motor.

Figure 1 is a front elevational view of our improved device; and Fig. 2 is a side elevational view thereof.

The combustion motor or engine comprises two oppositely disposed cylinders 1, provided with the usual operating appurtenances, which it has not been deemed necessary to illustrate in the present application. Intermediate the engine cylinders and con-

necting the same is the crank casing 2 to which is suitably connected the steering rod 45. Depending from the lower shaft bearing of the motor is an elongated sleeve 3, which is immovable in relation to the motor casing and envelops the motor shaft (not shown) and its extension. Formed integrally with or rigidly attached to the lower

end of the sleeve 3 is a gear box or casing 4 inclosing suitable gearing through the intermediary of which is driven the propeller shaft carrying the propeller 9. It is not thought necessary to illustrate either the

gearing or the propeller shaft in detail, as these parts are well-known in the art. Secured to or formed integrally with the sleeve 3 is a rudder 5, which may however be omitted as the steering of the boat may readily be effected through the propeller 9. 60

10 denotes a portion of the boat, supporting a clamp which is denoted generally as 11, and which carries a sleeve 6 in which the motor and appurtenant parts are adjustably and revolvably suspended. Clamped about the sleeve 3 is a collar 7, which is adjustable lengthwise of the sleeve 3, so that the motor may be suspended at a greater or less distance above the boat 10. Owing to the manner in which the motor is suspended for free revolution, as above described, the entire motor structure may be swung about the motor shaft as an axis so that the boat may be steered or its direction reversed by merely swinging the motor through the agency of the steering rod 8.

When a motor operates in water and the boat is steered or reversed there is a force which has a normal tendency to turn the entire motor structure in the direction of rotation of the motor shaft, and this necessitates the helmsman keeping his hand constantly on the steering rod so as to prevent the boat from becoming unmanageable. Owing to the fact that in the present structure the motor and its shaft together with the sleeve surrounding the same form practically a unitary structure, we obtain the advantage that the force which tends to rotate the motor system in the direction of rotation of the motor shaft is counteracted by the counter pressure of the motor on its cylinders, so that the work of the helmsman is rendered very much easier. The tendency of the entire motor system to be turned in the direction of rotation of the motor shaft is particularly noticeable in outboard motors of the type in which the motor is not an integral part of the remaining portions of the motor system, and in the use of such devices the helmsman is required to keep constant hold on the steering rod so as to prevent the boat from going in the wrong direction.

What we claim as new and desire to secure by Letters Patent is:—

1. In an outboard motor, the combination with a motor having a central crank casing, engine cylinders arranged symmet- 110

rically at opposite sides of the casing and an extended motor shaft in line with the crank casing, a propeller driven from said motor shaft, and a sleeve surrounding said 5 motor shaft and immovable relatively to the motor.

2. In an outboard motor, the combination with a motor having a central crank casing, engine cylinders arranged symmetrically at 10 opposite sides of the casing and an extended motor shaft in line with the crank casing, a propeller driven from said motor shaft, a sleeve surrounding said motor shaft and immovable relatively to the motor, and means 15 in which said sleeve is freely revoluble and by which said motor is supported.
3. In an outboard motor, the combination with a motor having a central crank casing,

engine cylinders arranged symmetrically at opposite sides of the casing and an extended 20 motor shaft in line with the crank casing, a propeller driven from said motor shaft, a sleeve surrounding said motor shaft and immovable relatively to the motor, means in which said sleeve is freely revoluble and by 25 which said motor is supported, and means lengthwise adjustable on said sleeve whereby the position of the motor in relation to the boat may be predetermined.

In testimony whereof we have affixed our 30 signatures in presence of two witnesses.

CARL ALRIK HULT.
OSCAR WALFRID HULT.
